Primary Examiner — Susan E Krakower*Assistant Examiner* — L. A. Grabenstetter(74) *Attorney, Agent, or Firm* — Russell Swerdon; Desmund Gean(57) **CLAIM**

The ornamental design for a camera, substantially as shown and described.

DESCRIPTION

FIG. 1 is a front top right side perspective view of a camera showing our new design;

FIG. 2 is a rear top left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in FIGS. 1-4 depict unclaimed portions of the camera.

1 Claim, 8 Drawing Sheets(56)
